(57) **CLAIM**

The ornamental design for a speaking valve with breathing filter for a tracheal tube as shown and described.

DESCRIPTION

FIG. 1 is a top view of the SPEAKING VALVE WITH BREATHING FILTER FOR A TRACHEAL TUBE;

FIG. 2 is a bottom view of the SPEAKING VALVE WITH BREATHING FILTER FOR A TRACHEAL TUBE;

FIG. 3 is a rear view of the SPEAKING VALVE WITH BREATHING FILTER FOR A TRACHEAL TUBE.

FIG. 4 is a side view seen from the left of the SPEAKING VALVE WITH BREATHING FILTER FOR A TRACHEAL TUBE;

FIG. 5 is a front view of the SPEAKING VALVE WITH BREATHING FILTER FOR A TRACHEAL TUBE;

FIG. 6 is a side view seen from right side of the SPEAKING VALVE WITH BREATHING FILTER FOR A TRACHEAL TUBE.

FIG. 7 is a perspective view seen from the rear of the SPEAKING VALVE WITH BREATHING FILTER FOR A TRACHEAL TUBE.

FIG. 8 is a perspective view seen from the front of the SPEAKING VALVE WITH BREATHING FILTER FOR A TRACHEAL TUBE;

FIG. 9 is a perspective bottom view seen from left side of the SPEAKING VALVE WITH BREATHING FILTER FOR A TRACHEAL TUBE;

FIG. 10 is a perspective bottom view seen from right side of the SPEAKING VALVE WITH BREATHING FILTER FOR A TRACHEAL TUBE.

The dot-dash and dash-dot broken lines illustrate portions of the SPEAKING VALVE WITH BREATHING FILTER FOR A TRACHEAL TUBE and does not form part of the claimed design.

1 Claim, 5 Drawing Sheets
